UNITED STATES PATENT OFFICE.

EDWARD B. HESS, OF NEW YORK, N. Y., AND JOSEPH M. STOUGHTON, OF NORWALK
OHIO, ASSIGNORS TO ROYAL TYPEWRITER COMPANY, OF NEW YORK, N. Y., A COR-
PORATION OF NEW JERSEY.

WRITING-MACHINE.

967,916.

Specification of Letters Patent. Patented Aug. 23, 1910.

Original application filed March 30, 1905, Serial No. 252,818. Divided and this application filed June 18,
1910. Serial No. 567,567.

To all whom it may concern:

Be it known that we, EDWARD B. HESS, of the borough of Manhattan, formerly of the borough of Brooklyn, city and State of New York, and JOSEPH M. STOUGHTON, of Norwalk, county of Huron, State of Ohio, formerly of the city of Yonkers, county of Westchester, and State of New York, citizens of the United States of America, have 5 invented certain new and useful Improvements in Writing-Machines, of which the following is a specification.

This invention relates to the keyboard construction of typewriting machines and 15 this application is a division of our application filed March 30, 1905, Serial Number 252,818. The keyboard construction may be used with type bar actuating devices other than those herein shown.

20 In the accompanying drawings which show so much only of the typewriting machine as will serve to illustrate the invention, Figure 1 is a vertical longitudinal section; Fig. 2, a bottom plan omitting the 25 platen, type bar segment and type bars, and showing the type-bar operating links broken away in front of their points of connection with the type-bars; Fig. 3, a detail plan of part of the stepped keyboard plate; and 30 Fig. 4, a vertical transverse section in line 4, 4, through part of the bottom horizontal key-board plate.

The main frame is shown, in this instance, as composed of an open rectangular casting 35 a provided on the bottom at each side with two cushion-feet a' of rubber or other suitable material. A front strike machine is shown, of which b is the platen, c the slotted type bar segment; and d type-bars, two 40 only being shown. The type-bars extend from the segment toward the front of the machine, and, as usual, rest normally upon a segmental rest e.

The construction of the type-bar segment 45 and pivoting of the bars therein may be of any appropriate character. As shown, d' is a pivot rod or wire common to the entire series of type-bars. The heel d' of each type-bar, below the segment, has connected 50 to it an operating link f which extends under the assemblage of type-bars, toward the front of the machine and is flexibly connected to the rear end of a shorter link

whose front end is pivotally connected to a fixed piece h, on the frame. In the construction illustrated the joint between the links f, g, is made by means of the end of the vertical stem i of a push pin finger piece i' in the key-board. The rear end of link f is formed with a hook or eye that engages in an aperture in the heel of the type-bar, such joint permitting, to the required extent, a universal movement. The front end of this link is provided with a snap hook j, by means of which it is engaged with the aperture nearest the end of the stem i. The rear end of the front link g is formed with a hook or eye which engages the upper aperture in the finger piece stem i, and the front end of this link is formed with a snap hook j, that engages an aperture in a lug or ear h punched on three sides from the horizontal bottom plate k of the key-board and turned down at right angles.

m is the stepped top plate of the key-board, there being four steps for the four series of finger pieces 1, 2, 3, 4, arranged as usual in lines transverse to the machine. There is, of course, for each type-bar a link f, a link g, and finger piece and stem. The lugs or ears h are arranged in a plane horizontal, or substantially so, in four transverse series corresponding to the transverse rows in the bank of finger pieces. The links f will, of course, extend rearwardly at varying angles from the horizontal depending upon the position of the corresponding type bar in the type bar segment. The arrangement of the lugs or fixed pieces or anchor points for the front ends of the front links 90 in a horizontal plane, or substantially so, but in separate transverse rows corresponding with the rows of the finger pieces, constitutes one of the leading features of this invention quite irrespective of any particular mode of hinging the pairs of links together at their adjacent ends or of operating the flexing connections formed by the links. The arrangement is one that permits of a low key-board, and the construction is 100 simple and economical because all of the anchor points may be conveniently and cheaply formed from a single piece of sheet metal. All of the parts may be held in the normal position indicated in Fig. 1 by 105 means of suitably applied springs.

In the present construction each link f has clamped, or otherwise rigidly attached to it, at a suitable point in front of the heel of the type-bar, a downwardly extending arm n . The entire series of such arms may be arranged in two transverse rows, those in the front row being preferably made somewhat longer than those in the rear row to afford proper clearance for all necessary movements. A coiled spring o having one end attached to the arm n extends rearwardly and has its rear end o' hooked into an aperture in the lower edge of a transverse vertically disposed plate p , the upper edge of which fits in a groove in the transverse rear frame plate and is supported by two adjusting screws p' passing loosely through apertures in the plate and working in threaded sockets in the frame plate. By manipulation of these screws, the tension of the entire series of springs for all the type bars may be simultaneously adjusted.

q is the universal bar extending between the rocking pendent arms q' and actuated as follows: From each arm n , a link extends through the coiled spring o and has its rear end formed with a hook of sufficient dimensions that embraces the universal bar, such degree of lost motion being provided as to effect actuation of the universal bar at the proper point in the traverse of the type-bars to the printing point on the platen. This arrangement of springs, the mode of adjusting them, and of the universal bar devices has been shown by experience to be practicable and efficient. Moreover, it is economical in construction and convenient to assemble. As seen in Fig. 3, the apertures r in the top plate of the key-board for the passage of the finger piece stems are formed with lateral enlargements to permit the passage of lateral pins i^2 on the stems, which constitute stops acting against the bottom of the bottom plate k to limit the upward movement of the stems. The slots in this bottom plate k , through which the stems of the finger pieces pass, are elongated, as shown, to provide for the angular movement of the stems when the finger piece is depressed, and are also formed with lateral enlargements to permit passage of the stop pins i^2 . The lateral enlargements in the slots in the stepped top plate m and in the bottom plate k are, of course, in corresponding sides of the slots, and the greater length of the slots in the bottom plate not only permits the angular movements of the stems in the operation of the machine, but also allows of manipulation of the stems in assembling. When the stems are in position they occupy the rear ends of the slots in the bottom plate and the stop pins i^2 are in rear of the lateral enlargements of such slots.

The arrangement of the slotted top plate m and slotted bottom plate k is such as to afford accurate guidance of the upper and lower portions of the flat finger piece stems during their vertical movements.

The type-bar actuating connection f , g , has the action of a breaking toggle and when the joint between the adjacent ends of the two links is moved downwardly the type-bar is thrown to the printing point with an increasing velocity. The particular angle at which the link g extends forward to its fixed anchor point may be varied as desired. The one shown affords highly satisfactory results.

We claim:

1. In a front strike typewriting machine, a sheet metal keyboard plate, common to a plurality of keys, having apertures for passage and guidance of finger piece push pins and integral downward projections formed by punching and bending that constitute fixed pieces for the connection of type bar operating means.

2. In a front strike typewriting machine, a flat horizontally disposed sheet metal keyboard plate, common to a plurality of keys, having apertures for passage and guidance of finger piece push pins and integral downward projections formed by punching and bending that constitute fixed pieces for the connection of type bar operating means.

3. A keyboard structure for a typewriting machine, comprising upper and lower fixed plates having correspondingly placed apertures with lateral enlargements on corresponding sides, combined with push pins, having lateral projections thereon, located and guided in said apertures.

4. A keyboard structure for a typewriting machine, comprising upper and lower fixed plates having corresponding slots for the reception and guidance of the upper and lower portions of finger piece push pins and downward projections integral with the lower plate for the connection of type bar operating connections to be actuated by the push pins.

5. A keyboard structure for a typewriting machine, comprising upper and lower fixed plates having correspondingly placed apertures with lateral enlargements on corresponding sides, combined with push pins, having lateral projections thereon located and guided in said apertures and downward projections integral with the lower plate for the connection of type bar operating connections to be actuated by the push pins.

6. A keyboard structure for a typewriting machine, comprising upper and lower fixed keyboard plates having corresponding apertures for the reception and guidance of finger piece push pins, the apertures in the lower plate being of greater dimensions fore and aft of the machine than those in the

upper plate for the purpose of allowing angular displacement of the push pins during their vertical movements.

7. A keyboard structure for a typewriting machine, comprising upper and lower fixed keyboard plates having corresponding apertures for the reception and guidance of finger piece push pins, the apertures in the lower plate being of greater dimensions fore and aft of the machine than those in the upper plate for the purpose of allowing angular displacement of the push pins during their vertical movements and downward projections integral with the lower plate for the connection of type bar operating connections to be actuated by the push pins.
8. A keyboard structure for a typewriting machine, comprising upper and lower fixed plates having corresponding apertures with lateral enlargements on corresponding sides, the apertures in the lower plate being of greater dimensions fore and aft of the machine than those in the upper plate, combined with push pins, having lateral projections, located and guided, in said apertures.
9. In a front strike typewriting machine, a sheet metal keyboard plate, common to a

plurality of keys, having apertures for passage and guidance of finger piece push pins and integral downward projections formed by punching and bending whose lower ends lie in substantially the same horizontal plane and that constitute fixed pieces for the connection of type bar operating means.

10. In a front strike typewriting machine, a flat horizontally disposed sheet metal keyboard plate, common to a plurality of keys, having apertures for passage and guidance of finger piece push pins and integral downward projections formed by punching and bending whose lower ends lie in substantially the same horizontal plane and that constitute fixed pieces for the connection of type bar operating means.

In testimony whereof, we have hereunto subscribed our names.
